UNITED STATES PATENT OFFICE.

ELBRIDGE G. LIBBY, OF MEDFORD, ASSIGNOR TO HIMSELF AND JOEL W. UPHAM, OF WORCESTER, MASSACHUSETTS.

IMPROVEMENT IN WATER-WHEELS.

Specification forming part of Letters Patent No. 127,076, dated May 21, 1872.

To all whom it may concern:

Be it known that I, ELBRIDGE G. LIBBY, of Medford, in the county of Middlesex and State of Massachusetts, have invented certain Improvements in Turbine Water-Wheels, of which the following is a full, clear, and exact description, reference being had to the accompanying drawing making part of this specification, in which—

Figure 1. is a perspective view of my improved water-wheel, detached. Fig. 2 is a horizontal section through the same. Fig. 3 is a perspective view of my improved bed-plate, provided with leading curves or passages for guiding the water into the wheel. Fig. 4 is an elevation of the bed-plate. Fig. 5 is a perspective view of the gate I employ. Fig. 6 is an elevation of the same. Fig. 7 is a vertical section through the center of the gate, bed-plate, and wheel, when put together and in a position ready for use.

In turbine water-wheels, as heretofore constructed, the floats or buckets have been placed in a vertical position between rims parallel to each other, and extending horizontally around the wheel; or the floats or buckets have been placed between vertical rims, also parallel to each other, and extending around the wheel. In the former case the water impinges on the buckets at an acute angle; and although it is discharged at the outer periphery of the wheel, yet its centrifugal force is only utilized to a limited extent; and, in the latter case, where the water strikes the floats and then passes down through the wheel, or in wheels where the water is discharged toward the center, the centrifugal force is entirely lost.

This invention consists in a bed-plate having the portion in which are formed the passages for guiding the water onto the buckets inclined down and toward the axis of the wheel, in combination with a wheel provided with floats or buckets inclined in the same direction as the inclined portion of the bed-plate, the rims, between which the floats are secured, being inclined downward and outward from the center, by which construction the water, as it leaves the leading curves, impinges at or nearly at right angles upon the surfaces of the floats or buckets, and is discharged at the periphery of the wheel, whereby the centrifugal

force of the water is utilized to a much greater extent than heretofore.

To enable others skilled in the art to understand and use my invention, I will proceed to describe the manner in which I have carried it out.

In the said drawing, A is the vertical shaft, the bottom of which rests upon a step, B, in the center of the wheel-pit C. To this shaft is attached the turbine-wheel D, provided with an upper rim, a, and a lower rim, b, which are parallel to each other, and inclined downward and outward from the center of the wheel. (See Fig. 7.) Between these rims, and at right angles thereto, are secured a series of floats or buckets, c, which are consequently inclined downward and inward, the surface of each float being curved, as seen in Fig. 2, the degree of curvature being greatest at its inner or inlet end. Upon the floor of the flume, over the top of the wheel-pit, rests an inclined bed-plate, E, (see Figs. 3 and 4,) which is horizontal from the point 10 to the point 11, and inclined from the point 12 to the point 13 down toward the axis of the wheel, passages d for guiding the water upon the floats or buckets being formed in this inclined portion 12 to 13, by which construction the water strikes the inner or inlet portion of each float c at or nearly at right angles, and passes down and outward from the center in about the same direction as it had when first impinging upon the floats, whereby the centrifugal force is utilized to a much greater extent than heretofore. e is a metallic sleeve, through which the shaft A passes, and by which it is steadied and held in a central position. This sleeve, when worn, can be readily replaced by another at a trifling cost. G, Fig. 5, is a register-gate placed upon the bed-plate, and turning around the shaft A as a center. This gate is provided with apertures f, corresponding in number and form to the apertures d in the bed-plate, the gate being also inclined at an angle similar to that of the inclined portion 12 to 13 of the bed-plate, and resting on the lower portion 13 of the same. The central portion of the bed-plate and that of the gate are of nearly conical form, a space, h, being left between them, into which the water flows through the openings i, the pressure of the water serving to slightly lift

the gate so as to relieve in a measure its friction on the inclined portion 13 of the bed-plate. The gate G is provided with a short rack, *k*, with which engages a pinion, *l*, the shaft of which revolves in bearings secured to the bed-plate, by which means the gate can be moved to increase or diminish the size of the inlet-apertures, through which the water is directed upon the floats or buckets, and the supply of water is thus regulated as required. *m m* are stops for preventing the gate from being turned too far in either direction.

Claims.

What I claim as my invention, and desire to secure by Letters Patent, is—

1. The bed-plate E, with its portion 12 to 13 inclined down and toward the axis of the

wheel, and provided with apertures *d*, in combination with a wheel, D, the floats or buckets of which are inclined downward and inward and discharge the water at its outer periphery, substantially as and for the purpose set forth.

2. I also claim an inclined gate, G, in combination with an inclined bed-plate, E, and wheel D, operating substantially in the manner and for the purpose set forth.

3. I also claim a gate, G, provided with openings *i*, substantially as and for the purpose described.

Witness my hand this 23d day of December, 1871.

ELBRIDGE G. LIBBY.

In presence of—

P. E. TESCHEMACHER,
W. J. CAMBRIDGE.
